(57) **CLAIM**

I claim the ornamental design for a speaker box, as shown and described.

DESCRIPTION

FIG. 1 is a front perspective view of a speaker box of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof; and,

FIG. 8 is an enlarged view of the area denoted by line 8-8 of FIG. 2.
